corporation of Delaware

Application May 21, 1941, Serial No. 394,440

10 Claims. (Cl. 196—52)

1

The present invention relates to improvements in effecting chemical reactions involving the contact of gas or vapors with a solid in finely divided condition. More particularly, the invention pertains to improvements in the conversion of hydrocarbons such as the conversion of high boiling hydrocarbons to lower boiling products by contacting the high boiling hydrocarbons in the vapor phase with a catalyst in a state of fine subdivision.

It has been proposed heretofore to catalytically convert high boiling hydrocarbons such as a petroleum gas oil to low boiling hydrocarbons within the gasoline boiling range by passing vapors of the high boiling hydrocarbons under suitable reaction conditions in contact with a stationary bed of a cracking catalyst. Pursuant to such processes, after the activity of the catalyst is decreased by reason of the formation of a carbonaceous deposit thereon to an extent where regeneration is necessary or desirable, the activity of the catalyst is restored by stopping the flow of oil vapor to the bed of catalyst and passing an oxygen-containing gas through the bed in contact with the spent catalyst, thereby regenerating it in situ by combustion of the carbonaceous deposit. Although such processes are commercially practicable they are subject to a number of inherent limitations and disadvantages. Among these are the intermittent nature of the operation, variations in product quality and quantity during the reaction period and difficulty in temperature control, particularly in the regeneration operation.

A process whereby these objectionable limitations and disadvantages of the stationary bed or intermittent type of conversion operation are largely eliminated is described in copending application Serial No. 390,164, filed April 24, 1941, in which applicant is a co-applicant. Pursuant to the latter process, the catalyst is introduced into the conversion and regeneration zones in finely divided or powdered condition and at the same time certain of the variable operating conditions are so controlled as to maintain a preferred concentration of the catalyst in said zones for the desired conversion and regeneration effects. One of the distinctive features of the process is the maintenance of a relatively low velocity of the vapors passing through the conversion and

regeneration zones whereby a dense phase or mass of the catalyst is maintained in these zones. In the case of the conversion zone, fresh catalyst is continuously added to said dense phase and corresponding amounts of used catalyst withdrawn therefrom at a rate adapted to maintain the average catalytic activity at a suitable value. Similarly, in the regeneration zone, spent catalyst is continuously added thereto and regenerated catalyst withdrawn therefrom. One of the most important features contributing to the satisfactory practice of such a process resides in the provision of an especially suitable method of separating the finely divided catalyst from the vapors or gases withdrawn from the conversion and regeneration zones. The present application is directed particularly to this feature of the process.

One method proposed for the separation of the catalyst from the mixture of gas and catalyst particles withdrawn from the conversion and regeneration zones involves withdrawing the mixture from said zones through a constricted outlet at a high velocity and passing it through cyclone separators to effect the desired separation under a relatively high vapor velocity condition. The present invention is based on the discovery that such methods of separation are not essential, and that the mixture withdrawn from the conversion and regeneration zones may be separated by a substantially more effective and less expensive method and apparatus than the cyclone separators or similar systems operating under high velocity heretofore considered necessary.

35 Pursuant to this invention, the gaseous mixture containing spent or regenerated catalyst withdrawn, respectively, from the conversion and regeneration zones, is passed into a separating zone of relatively large cross sectional area wherein 40 the mixture is separated into two phases, a lower dense catalyst phase and an upper phase consisting of gas mixed with a relatively small amount of suspended catalyst. A further feature of the process resides in the provision of means for maintaining the dense catalyst phase in a flowable condition and free of reaction vapors by the introduction of an aerating and stripping medium thereto, and means for withdrawing it at the required rate. An additional feature of 45 the process in its preferred aspect resides in the

withdrawal of the gas and catalyst mixture from the conversion and regeneration zones through a constricted outlet at a high velocity and impinging it against a deflecting surface or baffle positioned in the separating zone, the baffle being of a configuration especially adapted to facilitate the formation of the desired two distinct phases. Various other features and advantages of my invention will be apparent from the following detailed description of exemplary embodiments thereof given in connection with the appended drawings, wherein:

Fig. 1 is an elevation view of the combined reactor and used catalyst separator and the combined regenerator and regenerated catalyst separator, and illustrates the details of these elements and their interconnection.

Figs. 2 and 3 are views similar to Fig. 1 of modified embodiments of the invention.

Fig. 4 is an end elevational view of the assembly of regenerator separator and associated Cottrell precipitator.

Fig. 5 is a further modified embodiment of the invention.

Fig. 6 is a plan view further illustrating a preferred embodiment of the deflecting surface or baffle device.

Referring to Fig. 1, a fine divided or powdered active catalyst is introduced through the outlet 1 of a catalyst standpipe 31 into a stream of the feed vapors traveling at a relatively high velocity through the reactor inlet line 2. Both the catalyst and vapors preferably are heated prior to their mixture in their line 2 to an elevated temperature suitable for the subsequent conversion. Vaporized feed may be supplied to line 2 by a transfer line 3 leading from a suitable source of vaporized feed stock such as a pipe still heater. Catalyst thus introduced is picked up by the vapors and carried therewith through line 2 into a conical inlet 5 in the lower part of reactor 6. Reactor 6 is a vessel, in the form of a cylinder or other suitable shape, having a relatively great cross-sectional area compared to the cross-sectional area of the vapor inlet line 2, and these relative proportions cause a corresponding reduction in the velocity of the vapors after their passage from inlet line 2 into the reactor 6. The velocity of the vapors in reactor 6 is preferably maintained within such limits as to produce a concentrated or dense phase of the catalyst which state may conveniently be designated as "fluidized" or pseudo-liquid. This "fluidized" condition, in general, is characterized by the relatively high concentration of catalyst measured in terms of the quantity of catalyst per unit volume of reactor space, and by the maintained low velocity of reactant vapors through the reactor.

The reactant vapors travel upwardly through the reactor in contact with the fluidized catalyst and during this period of contact undergo the desired conversion. Operating conditions in the reactor determined by variables such as the dimensions of the reactor, and the temperatures and rates at which reactant vapors and catalyst are supplied thereto, are maintained within such limits as to bring about the desired quality and extent of conversion as exemplified and described in detail hereinafter.

The vaporous reaction products are withdrawn from the upper part of reactor 6 through a constricted outlet zone. The vapors pass from the upper portion of the reactor into the conical outlet 7 of progressively decreasing cross-sectional area in the direction of flow wherein their

velocity is progressively increased and then into an outlet pipe 8 likewise of relatively restricted cross-sectional area compared to that of the reactor. The vaporous conversion products mixed with spent catalyst exit through the outlet pipe 8 at a relatively high velocity into a settling chamber or collecting hopper 9 of relatively large cross-sectional area in the plane extending transversely to the direction of flow, this area preferably being such that the velocity of the vapors therein is of about the same order of magnitude but may be more or less than the vapor velocity in reactor 6. A deflecting surface or baffle 10, shown in plan in Fig. 6, is preferably interposed directly in the path of the vapor mixture exiting from pipe 8. The impinging surface of the baffle is preferably curved or is concave downwardly as shown so that the mixture is directed laterally and downwardly thus functioning to propel catalyst particles present in the mixture out of the path of the vapor flow into a quiescent collecting zone A defined by the outer walls of the outlet cone 7 and outlet pipe 8 and the lower inner walls of the settling or collecting hopper 9. The baffle may be circular in plan or any other suitable shape, however, the embodiment shown in plan view in Fig. 6 is especially advantageous since the catalyst separates primarily along the longitudinal edges 40 of the deflecting surface and the vapor flows axially of the baffle to a large extent and leaves the deflecting surface at the ends 41 thereof, thereby reducing the tendency of the catalyst particles to become resuspended in the vapor. Catalyst thus separated is continuously withdrawn through suitable means such as catalyst standpipe 11 opening into the lower part of the collecting zone A. A quantity of catalyst is preferably left at all times in said zone to maintain a level of catalyst therein at a substantial distance above the spent catalyst outlet opening as indicated by dotted line 12 and at a substantial distance below the vapor inlet line 8. Vaporous conversion products withdrawn through line 13 contain a relatively small portion of the catalyst originally present in the mixture passing through pipe 8.

Residual catalyst left in the vaporous conversion products exiting through line 13 to the products recovery system is separated in any suitable type of gas-solid separator such as the system of cyclone separators described in said application Serial No. 390,164 and may be returned to the spent catalyst in zone A through line 14.

A suitable inert aeriform medium such as steam is introduced through lines 15 having suitable fluid distributing means 16, in the bottom of the mass of catalyst in the collecting zone to maintain the mass in an aerated flowable condition and to strip or displace hydrocarbon vapors absorbed thereon or entrained therewith. While only two such lines 15 for introduction of the stripping medium are shown, it is to be understood that any suitable number may be employed and be so distributed throughout the collecting chamber as to assure the required stripping and aerating effects. The quantity of stripping steam employed is preferably such that its velocity in the collecting zone is low, that is, of the order of about 0.1 to 0.3 foot per second. The medium thus introduced and stripped oil vapors pass out of chamber 9 overhead through line 13 together with the vaporous conversion products.

As illustrative of operating conditions suit-

ably maintained in the reaction zone 6 and spent catalyst separating zone 8 and suitable dimensions for these zones, reference is made to the data tabulated in the following Table 1 setting forth typical design conditions suitable for a large scale commercial unit for a given type of charging stock and capacity.

Per cent of used catalyst withdrawn through standpipe 11	95.0

In conveying the spent catalyst from the spent catalyst collecting zone A to the regeneration zone suitable provision is made for any difference in pressure between these zones. A somewhat higher pressure is normally preferably maintained in the bottom or inlet portion of the regeneration zone than the pressure maintained in the collecting zone, and a head of suitably aerated or fluidized catalyst is preferably maintained in the outlet standpipe 11 of a sufficient magnitude to balance or exceed somewhat this differential pressure. For this purpose spent catalyst flowing through standpipe 11 is maintained in a condition in which it has the flow characteristics of a liquid by introducing in suitably regulated amounts an aerating medium such as steam through lines 17 at the bottom of and at other suitably spaced points along the length of pipe 11.

From the bottom of standpipe 11 spent catalyst is fed under the influence of the pressure head maintained therein and the pressure head provided by the mass of catalyst in zone A through a suitable feeding means such as a valve 18 into the regenerator inlet line 19.

Spent catalyst thus introduced is mixed with air or other suitable carrying medium such as steam introduced into pipe 19 by line 28. In case air is employed, the quantity introduced is so controlled that the combustion of the spent

catalyst in line 19 is not sufficient to raise the temperature of the catalyst beyond the maximum safe regeneration temperature.

The mixture of hot spent catalyst and carrying medium flows through line 19 into an inlet cone 20 at the bottom of the regenerator 21 where it meets and mixes with a stream of relatively cool recycled regenerated catalyst and air from cooler 22 and passes therewith upwardly 10 through the regeneration chamber 21.

In place of the above type of flow wherein the spent catalyst and recycled cooled catalyst are introduced separately into regenerator 21, I may utilize to advantage a modified flow comprising the introduction of the mixture of cooled catalyst and air withdrawn from exchanger 22 into line 20' in place of directly to the reactor. Due to the presence of the cooled recycled mixture in line 19, the possibility of an excessively high "flash" combustion temperature in line 19 is thereby obviated.

Operating conditions in the regeneration chamber or zone 21 are preferably maintained to provide a condition similar to that maintained in the reaction zone with respect to a "fluidized" condition of the catalyst. This condition similar to that maintained in the reactor is characterized by the relatively large concentration of catalyst and low vapor velocity maintained. During the course of the travel of the spent catalyst and air upwardly through regeneration chamber 21, combustion of the carbonaceous deposit on the used or spent catalyst is effected to the required extent at an elevated temperature maintained below the safe maximum regeneration temperature by means of the cooled recycled catalyst.

Gaseous regeneration products (flue gas) and regenerated catalyst exit from the upper part of the regenerator through a constricted outlet 23 and into a regenerated catalyst collecting hopper 24 similar in design and mode of operation to collecting hopper 9 described in connection with the reactor. The major portion of the regenerated catalyst is separated and collected in a collecting zone B at the bottom of hopper 24, and the gaseous combustion products together with a relatively small amount of regenerated catalyst pass out overhead through line 25 to any suitable type of gas-solid separating system such as that described in said copending application Serial No. 390,164. Catalyst recovered from the vapors in line 25 may suitably be returned to hopper 24 through line 26.

Suitable means 27 and 28, similar to pipe 15 and distributor 16, are provided in the lower portion of hopper 24 to introduce an inert aeriform medium such as steam to maintain the separated catalyst in an aerated flowable state and strip 60 and displace flue gas absorbed or entrained with the regenerated catalyst. Again as in the case of the reactor, a level of separated catalyst indicated by dotted line 29 is preferably maintained at a substantial distance below the top of outlet 23 and above the catalyst outlet lines 30 and 31.

Regenerated catalyst is preferably withdrawn from the collecting zone in hopper 24 in a split stream, a portion being sent through regenerated catalyst recycle line 30, and another portion 70 through regenerated catalyst line 31 leading to the conversion or reaction system. Both catalyst outlet lines 30 and 31 are pressure standpipes, similar to standpipe 11 in that they are provided with means for introducing an aerating medium at suitable points along their length so

7

as to maintain the catalyst flowing therethrough in a condition wherein it has the flow characteristics of a liquid, such means being lines 32 leading to recycle line 30 and lines 33 leading to catalyst outlet line 31. The quantity of catalyst withdrawn and recycled through line 30 is preferably maintained within predetermined limits so as to maintain the temperature in regeneration zone 21 within required limits in accordance with the principles of operation described in copending application Serial No. 274,670 (which issued as Patent No. 2,253,486 on August 19, 1941), and Serial No. 343,222, by Arnold Belchett, filed May 20, 1939, and June 29, 1940, respectively.

Regenerated recycle catalyst is fed from the bottom of standpipe 30 through a suitable feeding means such as a valve 34 into an inlet line 35 leading to a heat exchanger or catalyst recycle cooler 22. Regenerated catalyst thus introduced is picked up by air introduced into line 35 through line 36, the quantity of air thus introduced being sufficient together with any air introduced through line 20' to effect combustion to the required extent in the regenerator 21. From line 35 the mixture of air and regenerated catalyst passes through exchanger or cooler 22 wherein the temperature of the recycled catalyst is lowered by indirect heat exchange with a cooling medium circulated through the exchanger by lines 37 and 38.

Regenerated catalyst is fed to the conversion system from standpipe 31 through a suitable feeding means at the bottom thereof such as a valve 39 and line 1 into the stream of vapors to be converted passing through line 2 as previously described.

To exemplify operating conditions preferably maintained in the regeneration zone 21 and separating zone 24, and suitable dimensions for these zones, reference is made to the data tabulated in the following Table 2 wherein such data are given for a regeneration stage corresponding to the conversion stage tabulated in Table 1.

In the modified embodiment of the invention illustrated in Fig. 2, elements generally corresponding in their design and function to similar elements in Fig. 1 have been designated by corresponding numerals with the subscript *a*. Accordingly, detailed description of these particular elements is unnecessary. In this embodiment the vaporous mixture withdrawn from the reactor through constricted outlet 8a passes into one end of a horizontally extending separating zone 9a and the vapor inlet 13a is disposed at the opposite end portion of this zone thereby providing for the horizontal travel of the mixture of catalyst and gas a substantial distance through the separating zone whereby the efficiency of the separation is enhanced. A similar gas-solid separating arrangement 24a is employed to separate the regenerated catalyst from the gaseous mixture of regenerated catalyst and flue gas withdrawn through the constricted outlet 23a.

Since the flow of the mixture of catalyst and vapor is in a horizontal direction in separator 9a and 24a, the vertical cross-sectional area of each separator is made sufficiently large that the vapor velocity therein is relatively low, corresponding to the low vapor velocity maintained in separator 8. A baffle 10a, corresponding to baffle 10, may be provided directly in the path of the vapors flowing at a high velocity from reactor outlet pipe 8a, thereby facilitating the separation of the mixture into the desired lower dense catalyst phase and upper dilute phase of vapors mixed with a relatively small quantity of unseparated catalyst. In the lower part of the separating zone, means 15a are provided for introducing an aerating and stripping medium such as steam into the dense catalyst phase thereby maintaining it free of reaction product vapors and in a readily flowable condition. During the horizontal travel of the mixture through the separator, additional catalyst separates therefrom on to the dense catalyst phase and is carried to the outlet standpipe therewith. The efficiency of the separation is thereby enhanced, the extent thereof depending upon the length of the horizontal path through the reactor. The upper levels 12a and 29a of the separated dense catalyst phase are maintained at a predetermined distance from the vapor outlets 13a and 25a, respectively, by continuous withdrawal of the dense catalyst phase through the discharge standpipes, the rate of discharge being controlled by the valve at the lower end of the standpipe. The distance between the upper level of the dense catalyst phase and vapor outlet in each instance is such as to reduce the quantity of catalyst withdrawn overhead to a relatively small percentage of the catalyst present in the vapor mixture entering the separation zone. The dilute vapor phase exits from separator 9a through outlet 13a into a suitable gas solid separator such as a Cottrell precipitator 42. This precipitator may be of conventional design, in which

the reaction vapors are withdrawn overhead through line 43 and separated solids at the bottom through a suitable hopper. Solids separated in precipitator 42 are returned to the lower dense phase by hopper 14a which preferably extends slightly below the upper level of the dense phase as shown. The separated spent catalyst is withdrawn from separator 9a through catalyst stand-pipe 11a to which a suitable aerating medium is supplied through lines 17a. Separator 24a for separating regenerated catalyst from the gaseous mixture withdrawn through the constricted outlet 23a is of a generally similar design and operates on principles similar to separator 9a. The only material difference is in that in the regeneration stage, an alternative flow arrangement is illustrated wherein the constricted outlet 23a terminates at the top of the separator and no baffle is employed. Figure 4 is an end view of separator 24a and the associated Cottrell precipitator 44, and shows the relationship between the vapor outlet 25a and hopper 26a for returning catalyst recovered in the Cottrell precipitator 44 below the level of the dense catalyst phase.

Figure 3 illustrates a further modification similar to Figure 2 in all material particulars except for the omission of the constricted outlets 8a and 23a leading from the conversion and regeneration zones, respectively, to the corresponding separators. Elements of this figure corresponding in function to those of Figure 2 are identified with a similar numeral with the subscript b. In this embodiment the mixture of the vapors and catalyst withdrawn from the conversion and regeneration zones passes directly into the separating zone with little or no intervening change in velocity by reason of the omission of the constricted outlet 8a and 23a.

Figure 5 illustrates a further modification of the separator of the type represented by 9 and 24 in Fig. 1. Elements of Fig. 5 corresponding to those in Fig. 1 are indicated by similar reference numerals with the subscript c. In the embodiment shown in Fig. 5, an additional deflecting surface or baffle 46 similar to baffle 45c is disposed in a series or tandem arrangement therewith, together with means for increasing the velocity of the vapor leaving the first baffle and impinging it at this increased velocity against the second baffle 46. These means comprise a hood 47 enclosing the first baffle 45c and having its lower periphery extending below the level of the separated catalyst and terminating at its upper periphery in a high velocity outlet constituted by upwardly converging cone 48 and outlet pipe 49. Catalyst deflected from baffle 46 passes between the narrow annular space between hood 47 and inner walls of hopper 24c and combines with previously separated catalyst from baffle 45c.

In the practice of the invention operating conditions in the conversion and regeneration zones are preferably regulated as set forth in the above mentioned application, Serial No. 390,164, and particularly so as to provide a relatively dense or concentrated phase of the catalyst in these zones. To obtain this result low vapor velocities less than 6 ft./second and preferably less than 4 ft./second or less are contemplated. The range of vapor velocity ranges regarded as especially suitable is that extending from about 1.5 to about 2 ft./second.

It is to be understood that the various embodiments of the invention described in the foregoing are illustrative of its preferred practice and that various modifications may be made

thereon without departing from the essential features of the invention.

I claim:

1. A process for the continuous catalytic conversion of hydrocarbons, which comprises continually effecting the following steps, introducing a catalyst in powdered condition to a catalytic conversion zone, flowing vapors of the hydrocarbons undergoing conversion upwardly through said zone at a velocity sufficiently low to maintain the catalyst in said zone in a pseudo-liquid condition characterized by the relatively high concentration of the catalyst particles therein, adding fresh powdered catalyst to said pseudo-liquid dense phase at a rate adapted to maintain it and its average catalytic activity at a suitable value, withdrawing a mixture of vaporous reaction products and used catalyst from the upper part of the conversion zone and passing the mixture into a separating zone of large cross-sectional area approximating that of the conversion zone at right angles to the direction of vapor flow and deflecting the catalyst particles out of the direct path of vapor flow through said separating zone whereby said mixture is separated into two phases, a lower dense catalyst phase and an upper phase consisting of the vaporous reaction products mixed with a relatively small quantity of residual catalyst, introducing an inert gas throughout said lower dense phase in amount suitable to strip hydrocarbons entrained therewith and to maintain said phase in a flowable condition, and continuously withdrawing both said phases from the separating zone.
2. A process for continuously effecting chemical conversions involving contacting a gas with a solid material, which comprises continually effecting the following steps—introducing the solid material in powdered condition to a conversion zone, flowing the gas upwardly through said zone at a velocity sufficiently low to maintain the powdered material in said zone in a pseudo-liquid condition characterized by the relatively high concentration of the particles therein, continually adding additional quantities of the powdered material to said pseudo-liquid dense phase at a rate adapted to maintain it and its average activity at a suitable value, withdrawing a mixture of vaporous reaction products and treated solid particles from the upper part of the conversion zone and passing the mixture into a separating zone of large cross-sectional area approximating that of the conversion zone at right angles to the direction of vapor flow and deflecting the particles out of the direct path of vapor flow through said separating zone whereby said mixture is separated into two phases, a lower dense solid particles phase and an upper phase consisting of the vaporous reaction products mixed with a relatively small quantity of solid particles, introducing an inert gas throughout said lower dense phase in amount suitable to strip treated gas entrained therewith and to maintain said phase in a flowable condition, and continuously withdrawing both said phases from the separating zone.
3. A process for continuously regenerating powdered spent solid particles having a deposit of carbonaceous material thereon, which comprises continually effecting the following steps—introducing the particles to a regeneration zone, flowing an oxygen-containing gas upwardly through said zone at a velocity sufficiently low to maintain the solid particles in said zone in a pseudo-liquid condition characterized by the

relatively high concentration of the solid particles therein, continually adding spent solid particles to said pseudo-liquid dense phase at a rate adapted to maintain said pseudo-liquid phase, withdrawing a mixture of gaseous combustion products and regenerated solid particles from the upper part of the regeneration zone and passing the mixture into a separating zone of large cross-sectional area approximating the cross-sectional area of the regeneration zone at right angles to the direction of gas flow and deflecting the catalyst particles out of the direct path of gas flow through said separating zone whereby said mixture is separated into two phases, a lower dense solid particles phase and an upper phase consisting of the gaseous combustion products mixed with a relatively small quantity of residual solid particles, introducing an inert gas throughout said lower dense phase in amount suitable to strip gaseous combustion products entrained therewith and to maintain said phase in a flowable condition, and continuously withdrawing both said phases from the separating zone.

4. A process as defined in claim 3 wherein the velocity of the oxygen-containing stream through the regeneration zone is maintained within the range of about 1.5 to 4' per second.

5. A process for the continuous catalytic conversion of hydrocarbons which comprises continually effecting the following steps—introducing a catalyst in powdered condition to a catalytic conversion zone, flowing vapors of the hydrocarbons undergoing conversion upwardly through said zone at a velocity sufficiently low to maintain the powdered catalyst in said zone in a pseudo-liquid condition characterized by the relatively high concentration of the catalyst particles therein, continually adding fresh catalyst to the pseudo-liquid dense phase of catalyst in said conversion zone at a rate adapted to maintain it and the average catalytic activity of the catalyst therein at a suitable value, withdrawing a mixture of vaporous reaction products and used catalyst from the upper part of the conversion zone through a constricted outlet at a high velocity relative to that maintained in the conversion zone, used catalyst being present in said withdrawn mixture in amount corresponding to that at which fresh catalyst is added to the dense phase, impinging the mixture at said high velocity against a deflecting surface disposed in a separating zone of relatively large cross-sectional area approximating that of the conversion zone and deflecting the catalyst particles out of the direct path of vapor flow through the separating zone whereby said mixture is separated into two phases, a lower dense catalyst phase and an upper phase consisting of the vaporous reaction products mixed with a relatively small quantity of residual catalyst, introducing an inert gas throughout said lower dense phase in amount suitable to strip vapor or gas entrained therewith and to maintain said phase in a flowable condition, and continuously withdrawing both said phases from the separating zone.

6. A process for continuously effecting chemical conversions involving contacting a gas with a solid material, which comprises continually effecting the following steps—introducing the solid material in powdered condition to a conversion zone, flowing the gas upwardly through said zone at a velocity sufficiently low to maintain the solid particles in said zone in a pseudo-liquid condition characterized by the relatively high concentration of the particles of solid ma-

terial therein, adding additional quantities of said solid particles to said pseudo-liquid dense phase at a rate adapted to maintain its average activity at a suitable value and said pseudo-liquid condition, withdrawing a mixture of vaporous reaction products and treated solid particles from the upper part of the conversion zone through a constricted outlet at a high velocity relative to that maintained in the conversion zone, treated catalyst particles being present in said withdrawn mixture in amount corresponding to that at which additional quantities of the solid particles are added to the dense phase, passing the mixture from the high velocity outlet zone into a separating zone of relatively large cross-sectional area approximating that of the conversion zone and deflecting the catalyst particles out of the direct path of vapor flow through the separating zone whereby said mixture is separated into two phases, a lower dense phase of solid particles and an upper phase consisting of gaseous reaction products mixed with a relatively small quantity of unseparated solid particles, introducing an inert gas throughout said lower dense phase in amount suitable to strip vapor or gas entrained therewith and to maintain said phase in a flowable condition, and continuously withdrawing both said phases from the separating zone.

7. A process for the continuous catalytic conversion of hydrocarbons, which comprises continually effecting the following steps—introducing a catalyst in powdered condition to a catalytic conversion zone, flowing vapors of the hydrocarbons undergoing conversion upwardly through said zone at a velocity sufficiently low to maintain the powdered catalyst in said zone in a pseudo-liquid condition characterized by the relatively high concentration of the catalyst particles therein, adding fresh catalyst to said pseudo-liquid dense phase at a rate adapted to maintain it and its average catalytic activity at a suitable value, withdrawing a mixture of vaporous reaction products and used catalyst from the upper part of the conversion zone through a constricted outlet at a high velocity relative to that maintained in the conversion zone, used catalyst being present in said withdrawn mixture in amount corresponding to that at which fresh catalyst is added to the dense phase, passing the mixture from the high velocity outlet zone into a separating zone of relatively large cross-sectional area approximating that of the conversion zone and deflecting the catalyst particles out of the direct path of vapor flow through said separating zone whereby said mixture is separated into two phases having a horizontally extending interface therebetween, a lower dense catalyst phase and an upper phase consisting of the vaporous reaction products mixed with a relatively small quantity of residual catalyst, introducing an inert gas throughout said lower dense phase in amount suitable to strip hydrocarbons entrained therewith and to maintain said phase in a flowable condition, and continuously withdrawing both said phases from the separating zone.

8. A process for the continuous catalytic conversion of hydrocarbons which comprises continually effecting the following steps—introducing a catalyst in powdered condition to a catalytic conversion zone, flowing vapors of the hydrocarbons undergoing conversion upwardly through said zone at a velocity sufficiently low to maintain the powdered catalyst in said zone in a pseudo-liquid condition characterized by

the relatively high concentration of the catalyst particles therein, adding fresh catalyst to said pseudo-liquid dense phase at a rate adapted to maintain it and its average catalytic activity at a suitable value, withdrawing a mixture of vaporous reaction products and used catalyst from the upper part of the conversion zone through a constricted outlet at a high velocity relative to that maintained in the conversion zone, used catalyst being present in said withdrawn mixture in amount corresponding to that at which fresh catalyst is added to the dense phase, passing the mixture from the high velocity outlet zone into a separating zone of relatively large cross-sectional area approximating that of the conversion zone and deflecting the catalyst particles out of the direct path of vapor flow through the separating zone whereby said mixture is separated into two phases, a lower dense catalyst phase and an upper vapor phase consisting of the vaporous reaction products mixed with a relatively small quantity of residual catalyst, introducing an inert gas throughout said lower dense phase in amount suitable to strip vapor or gas entrained therewith and to maintain said phase in a flowable condition, and continuously withdrawing both said phases from the separating zone, the rate of withdrawal of the dense phase being such as to maintain the upper level thereof a substantial distance below the outlet for withdrawing the vapor phase and sufficient to reduce the catalyst withdrawn in the vapor phase to a minor amount.

9. A process for the continuous catalytic conversion of hydrocarbons, which comprises continually effecting the following steps—introducing a powdered catalyst to a catalytic conversion zone, flowing vapors of the hydrocarbons undergoing conversion upwardly through said zone at a velocity within the range of about 1.5 to 4' per second and adapted to maintain the powdered catalyst particles in said zone in a pseudo-liquid condition characterized by the relatively high concentration of catalyst therein, adding fresh catalyst to said dense pseudo-liquid phase at a rate adapted to maintain it and its average catalytic activity at a suitable value, withdrawing a mixture of vaporous reaction products and used catalyst from the upper part of the conversion zone into a separating zone having a cross-sectional area in the direction of vapor flow adapted to maintain the velocity of the vapor stream in said zone of the same order of magnitude as the vapor velocity through the conversion zone and deflecting the catalyst particles out of the direct path of vapor flow whereby said mixture is separated into two phases, a lower dense catalyst phase and an upper phase consisting of the vaporous reaction products mixed with a relatively small quantity of residual catalyst, introducing an inert gas throughout said lower dense

phase in amount suitable to strip hydrocarbons entrained therewith and to maintain said phase in a flowable condition, and continuously withdrawing both said phases from the separating zone.

10. A process for the continuous catalytic cracking of high boiling hydrocarbons which comprises continually adding a finely divided powdered cracking catalyst to a vapor-catalyst cracking zone at a rate sufficient to produce and maintain the pseudo-liquid mass mentioned below, continually passing a vapor stream of the high boiling hydrocarbons upwardly through said zone at a relatively low velocity within the range of about 1.5 to 4' per second and adapted to maintain a highly turbulent fluidized pseudo-liquid mass of the powdered catalyst particles in said zone, and then passing the vapor stream and added catalyst through a separating zone having a cross-sectional area at right angles to the direction of vapor flow of about the same order of magnitude as the corresponding area in the contacting zone and adapted to maintain the vapor velocities in both of said zones of the same order of magnitude, continually deflecting the powdered catalyst particles out of the path of vapor flow in said separating zone to produce therein a lower dense catalyst phase and an upper phase consisting of the vaporous reaction products mixed with a relatively small quantity of residual catalyst, introducing an inert gas throughout said lower dense phase in amount suitable to strip hydrocarbons entrained therewith and to maintain said phase in a flowable condition, and continually withdrawing by gravity-flow catalyst particles from said flowable lower dense phase at a rate sufficiently high to thus withdraw and separate a major amount of the continually added catalyst.

Certificate of Correction

Patent No. 2,439,811.

April 20, 1948.

JOSEPH W. JEWELL

It is hereby certified that errors appear in the printed specification of the above numbered patent requiring correction as follows: Column 3, line 28, for the word "fine" read *finely*; line 53, before "pseudo" and after "liquid" insert quotation marks; column 8, line 24, for "inlet" read *outlet*; column 9, line 30, for "correponding" read *corresponding*; line 50, insert a period after "baffle 46"; column 10, line 11, claim 1, for "the catalyst" read *the powdered catalyst*; line 14, same claim, after "fresh" strike out *powdered*; and that the said Letters Patent should be read with these corrections therein that the same may conform to the record of the case in the Patent Office.

Signed and sealed this 22nd day of June, A. D. 1948.
